JACK

Frank S. Pearne, Alhambra, Calif., assignor to
Regent Jack Mfg. Co., Inc., Los Angeles, Calif.,
a corporation of California

Application June 26, 1952, Serial No. 20,363

Term of patent 3½ years

(Cl. D41—1)

To all whom it may concern:

Be it known that I, Frank S. Pearne, a citizen of the United States, residing in the city of Alhambra, county of Los Angeles, and State of California, have invented a new, original, and ornamental Design for a Jack, of which the following is a specification, reference being had to the accompanying drawings, forming a part thereof.

Fig. 1 is a perspective view of a jack, showing the top, side and one end, embodying my new design. Fig. 2 is a perspective of the jack, showing the other side and other end. Fig. 3 is a side elevation. Fig. 4 is a front end elevation. Fig. 5 is a rear elevation and Fig. 6 is a top plan view thereof.

I claim:

The ornamental design for a jack, as shown.
FRANK S. PEARNE.
